UNITED STATES PATENT OFFICE.

CLYDE P. ROSS, OF CHICAGO, ILLINOIS.

COMBINED COAL AND CINDER HOIST.

Application filed June 26, 1922. Serial No. 570,765.

To all whom it may concern:

Be it known that I, CLYDE P. ROSS, a citizen of the United States, residing at Chicago, in the county of Cook and State 5 of Illinois, have invented a certain new and useful Improvement in Combined Coal and Cinder Hoists, of which the following is a specification.

My invention relates to a process of simultaneously or substantially simultaneously coaling engines and removing the cinders and ashes therefrom and to an apparatus for accomplishing this result. It is understood that in railroad yards where locomotives 10 are being handled and prepared for runs, it is desirable as quickly and as simply as possible to remove the cinders from a locomotive and to supply the locomotives with coal. It is the purpose of the present invention to simplify this essential process in the care of locomotives. Other objects will appear from time to time in the course of the specification and claims.

I illustrate my invention more or less diagrammatically in the following drawings, wherein:

Figure 1, is a side elevation with parts in section;

Figure 2, is an end view of the upper portion of the device shown in Figure 1; and

Figure 3, is a plan view.

A is any suitable tower structure, herein diagrammatically illustrated, having a foundation A¹ and supporting at its top a platform A².

Mounted on the tower is the chute B which is outwardly inclined at any suitable angle. The upper, funnelled receiving portion B¹ is supported by a vertical shaft B² which rotates in any suitable bearing B³ mounted for example at the intersection of the bracing members B⁴. It is supported at its bottom in any suitable bearing B⁵ on the base B⁶. The outer end of the chute is supported by a horizontal frame element C, secured to the shaft B² intermediate its length. It is further supported and braced by the upwardly inclined element C¹ the bottom of which is secured to the shaft B² adjacent its bottom. Thus the entire chute structure is thoroughly reenforced and is freely rotatable about a vertical axis. The rotation is controlled, for example by a bevelled gear D adjacent the bottom of the shaft B², in mesh with the bevelled pinion D¹ which may be rotated by

the hand crank D² or by any other suitable control mechanism.

The tower is positioned between two parallel tracks E and F having beneath them respectively the hoppers E¹ and F¹ which may be of varying size, but for which a single description will suffice. The hopper gate E² may be controlled by any suitable closure and control mechanism therefor, not herein described in detail. Underlying the hopper gate is the chamber E⁵ which is the innermost portion of the inclined passage E³ which at the foot of the tower converges upon the similar passage F³. In the bottom of these passages are the tracks E⁴ F⁴ which converge and are provided with a switch G having any suitable control means G² therefor. From the point of intersection rises the inclined single track G¹ which passes through the opening G² and is supported 75 at its upper end in any suitable manner on the tower A.

Adapted to travel on the tracks E⁴ F⁴ and up the track G¹ is the wheeled carriage or bucket H having two pairs of wheels H¹ H² 80 on its bottom and a pair of wheels H³ adjacent the top of one side. The angular relation of the pairs of wheels is such that the lower two pairs support the bucket when it is travelling on the tracks E⁴ or F⁴, the overlying guide H⁴ preventing vertical motion or tilting of the bucket. When the bucket passes over the switch the wheels H³ engage the steeply inclined track G¹ and the angular relation of the wheels H² and H³ 85 is such that the bucket travels up the inclined track with its top substantially horizontal. The axles of the wheels H³ are shorter than those of the wheels H². Adjacent the top of the track G¹ and lying on each side of it are a plurality of track sections H⁵ which lie respectively outside of each of the tracks G¹ and are inclined upwardly in relation thereto. When the carriage reaches the top of the track G¹, the 90 extending axle ends of the wheels H² contact and ride up over the inclined broad track portions H⁵, while the wheels H³ ride out over a curved or inclined track section H⁶, which is a continuation of the track G¹ 95 and is of the same width. The result is such a tilting of the carriage as is shown in Figure 1, the material being dropped from the carriage and against the baffle plate H⁷ and into the funnel mouth B¹ of the chute B. 110

The carriage returns by gravity to position beneath one or the other of the hoppers. When filled it is raised by a cable J which is secured to the pivoted yoke J¹ and passes over the sheave J² on the tower, being actuated for example by the hoist J³ which may be driven by any suitable mechanical means. When the carriage is beneath one of the hoppers the cable J passes over the sheave J⁵ which is swivelled and provided with any suitable centering guides J⁶.

While in the drawings herein I have illustrated the hoist J³ as on the ground and roughly between the two hoppers, under some circumstances it may be desirable to position the hoisting mechanism at the top of the tower, for example on the platform A².

I wish my description and drawings to be taken as in a large sense diagrammatic, and it will be realized that while I have illustrated an operative device, many changes might be made in the size, number, shape, relation and disposition of parts without departing from the spirit of my invention.

The use and operation of my invention are as follows:

Every locomotive must, at frequent intervals, be supplied with coal and be delivered of its ashes or cinders. I have developed an improved method for performing the two functions together, and I illustrate herein a peculiarly simple and efficient apparatus for handling both coal and cinders. In the track layout illustrated in Figure 3 the track on which the locomotive is placed is parallel with the track on which the coal and cinder cars stand. For convenience the tracks may be separated by the space which would normally be taken up by an additional track. In this space is positioned a loading tower on which is placed any suitable means for feeding material over either track. As a convenient mechanism for this purpose I illustrate a pivoted chute which may be swung over either track to deliver coal to the locomotive tender and cinders to the cinder car on the other track. Under each track is positioned a receiving hopper with any suitable gate control. Under each hopper is space for a conveying carriage or bucket and into this space runs a bucket track. The two tracks converge and are provided with a switch and a single track continues to the top of the loading tower. Any suitable means may be provided for moving the bucket, but I illustrate a cable and hoist.

In using this apparatus a coal car is spotted over a hopper E¹ and a cinder car is spotted adjacent the pivoted chute and on the same track. On the other track the locomotive is spotted with its fire box over the hopper F¹ and the tender near the chute. The cinders are dropped into the cinder hopper and gather there until the conveying

carriage or bucket is positioned therebeneath. They are then released into the bucket and conveyed upwardly to the top of the tower where they are dropped into the chute, which delivers them to the cinder car. Coal is dropped into the other hopper, and either before or after the cinders have been disposed of the same bucket is positioned beneath the coal hopper and filled. The bucket then is drawn to the top of the tower and discharges the coal into the chute, the chute being rotated into position to deliver coal to the locomotive tender. The coal hopper may if desired be of such size as to hold the entire car load of coal and the cinder hopper or pocket may be large enough to receive cinders from one or more locomotives. The operator by controlling the switch G directs the bucket under the coal or the cinder hopper and by means of the gear D and pinion D¹ directs the chute to the proper track. These operations may be performed manually and separately, or a central control system may be used, the details of which it is not necessary here to describe.

I claim:

1. An installation for handling materials comprising a plurality of adjacent tracks, a hopper beneath each track, material delivery means adjacent the tracks and means for delivering material therefrom over either track, and a conveyor adapted to convey material from either hopper to the top of said tower, said conveyor comprising a forked track having a branch underlying each hopper.

2. An installation for handling materials comprising a pair of adjacent tracks, a material receiving hopper adjacent each track, a delivery tower positioned between said tracks and means thereon adapted to deliver material over either track, a conveyor bucket, a track therefor, said track being forked and having a section underlying each hopper, means for positioning the bucket beneath either hopper, means for feeding material to it from either hopper, and means for lifting the bucket to the top of the tower and for dumping the material into said delivery means.

3. In a combined coaling and cinder removing installation adapted to coal and to de-cinder locomotives substantially simultaneously, a plurality of adjacent tracks, hoppers underlying each track, material delivery means adjacent said tracks and adapted to deliver materials over either track at a substantial distance along said track from said hoppers, and means for conveying materials from either hopper to said material delivery means.

4. In a combined coaling and cinder removing installation adapted to coal and to de-cinder locomotives substantially simulta-

- neously, a plurality of adjacent tracks, hoppers underlying each track, material delivery means adjacent said tracks and adapted to deliver materials over either track at a substantial distance along said track from said hoppers, and means for conveying materials from either hopper to said material delivery means, comprising a forked conveyor track having a branch adjacent each hopper, a switch at the junction of said forks, a hoist adapted to ride on said tracks, means for raising said hoist to a level substantially above said tracks, and means for receiving material delivered by said hoist and for directing it over either track. 5
10. In a combined coaling and de-cindering plant for locomotives adapted to handle coal and cinder cars simultaneously, a plurality of adjacent tracks, a material-receiving hopper beneath each track, means adapted to deliver material over either track at a point substantially removed along said track from said hopper and conveying means adapted to deliver material from either hopper to said material delivery means. 20
15. In a combined coaling and cinder removing installation adapted to handle coal and cinder cars substantially simultaneously, a plurality of adjacent tracks, a hopper beneath each track, a delivery tower intermediate said tracks, means for delivering material from said delivery tower over either track, and means for conveying material from either hopper to a point adjacent the top of said delivery tower, comprising a forked track having a branch underlying each hopper, and a receptacle adapted to move on said track and means for hoisting it along said track. 30
25. In a combined coaling and de-cindering plant for locomotives, adapted to handle coal and cinder cars simultaneously, a plurality of adjacent tracks, a receiving hopper positioned beneath each of said tracks, a delivery means adapted to deliver material over either track at a point positioned at a substantial distance along the tracks from the hoppers, and means for conveying materials from beneath said hoppers along and above said tracks to said material delivery means. 35
6. In a combined coaling and cinder removing installation adapted to handle coal

7. In a combined coaling and de-cindering plant for locomotives, adapted to handle coal and cinder cars simultaneously, a plurality of adjacent tracks, a receiving hopper positioned beneath each of said tracks, a delivery means adapted to deliver material over either track at a point positioned at a substantial distance along the tracks from the hoppers, and means for conveying materials from beneath said hoppers along and above said tracks to said material delivery means. 40

Signed at Chicago, county of Cook and State of Illinois, this 22nd day of June, 1922.

CLYDE P. ROSS.
